UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed October 16, 1923. Serial No. 668,821.

The invention relates to typewriting machines, and particularly to machines of the kind known as continuous web or fan-fold machines, as set forth in the patent to Werner & Smith, No. 1,132,055, of March 16, 1915, and is an improvement on the patent to A. A. Johnson, No. 1,548,320, of August 4, 1925, and on my pending application, Serial No. 664,844, filed September 26, 1923.

One of the principal objects of the present invention is to economize in carbon-paper, and to reduce the time which is taken by replacing worn-out carbon-sheets.

In general it is further the object of the invention to simplify the operation of such machines.

These and other objects and advantages are achieved by using carbon-sheets which are longer than the sheets heretofore required for one form, bill or letter, to such an extent that the extra length of carbon-sheet provides a reserve to be utilized after the leading portion of the carbon-sheet has become worn and exhausted by use. The means for bringing a fresh portion of the carbon-sheet by a simple and short manipulation into working position forms part of this invention.

According to this invention carbon-sheets, which are of sufficient length to provide for two or more forms or web sections, are preferably folded over a holder-blade, so that the normally inactive extra length or reserve portion extends forward over the active or leading portion toward the platen in the form of a loop at the rear of the platen, and then the folded carbon-sheet is clamped to the blade to be inserted between the adjoining plies of the web.

When the leading portion of the carbon-sheet has become worn the extra portion can be made available by releasing the clamp which fastens the carbon-sheets upon the holder-blade and slowly pushing the carbon-holder truck to the rear to pay out the loop. This simple and short operation effects relative shifting between the carbon-sheet and the carbon-holder, and thereby brings a normally inactive fresh portion of the carbon-sheets into active working position. The exhausted leading portion of the carbon-sheets may thereafter be severed together

with the last typed workpiece section from the front end of the web.

Provision is made for releasing the carbon-sheet from the blade without disturbance or removal of the blade from between the webs and without removal of the carbons from between the web-plies. For this purpose, locking and releasing means are provided which are operable from the outside of the web, without parting the web-plies.

Provision is also made for simultaneously releasing and clamping several carbon-sheets or all of the sheets.

The extra length of carbon available may give double or triple service and only a small portion of the original length of carbon is wasted.

It is also a feature of the invention that the overlapping reach or excess part of the sheet, by registration or alignment of the side edges thereof with the side edges of the other reach of the sheet, may serve as a means for assuring that the sheet is not attached to the carrier in skewed condition.

Other features and advantages will hereinafter appear.

In the accompanying drawings,

Figure 1 shows a sectional elevation of a portion of a continuous billing or fan-fold typewriter embodying the invention.

Figure 2 is a diagrammatic view of a section of a carbon-sheet clamped in the preferred way.

Figure 3 is a top view of the truck on which the carbon-holders are mounted, showing a plurality of clamps arranged in position to grip the carbon-sheets.

Figure 4 is the same as Figure 3, but shows the clamps in the position to release the carbon-sheets.

Figure 5 is a fragment of a perspective view of the carbon-holder and its bearing shown as in the position of Figure 3.

Figure 6 is an enlarged detail of the holding and clamping means taken along section line 6-6 in Figure 3, each holding and clamping means forming an easily detachable unit.

Referring to the drawings, there is shown a portion of a billing machine for typing a plurality of continuous plies of fan-fold

webs interleaved with carbon-sheets. A platen 10 is mounted on a platen-shaft 11, which is journaled on a platen-displacing frame 12. The platen 10 together with the frame 12 and a front paper-table 13, mounted thereon, are swingable about the shaft 14, and are held in lowered or typing position by latches 15. A rear paper-table 16 is fastened on a cross-bar 17 of the machine, and passes under and around the platen 10 when the latter is in typewriting position. The paper-table 16 assists in feeding the composite work-piece around the platen 10.

A carbon-holder truck 18 is mounted in the rear of the machine on rails 19 to ride forward and backward. On one side of the truck 18 (left-hand side in Figures 1 and 3), fastened by any suitable means, as by nuts and screws, designated together as 35, is a handle 36 arranged within reach of the operator. By means of this handle 36 the truck 18 may be pulled toward, or pushed away from, the platen 10.

The above-described parts of the machine are like those of the well-known Underwood continuous billing typewriter, described in the above-mentioned patent to Wernery & Smith, No. 1,132,055.

In accordance with the present invention, there is preferably mounted longitudinally on each side of the truck 18 a stepped bearing block 20. Each step of the blocks in this instance has in staggered relation holes 21 extending downward from the upper side of each step to receive pins 22, which depend rigidly from the under face of a carbon-holder blade 23, as shown in detail in Figure 6, for holding the blades 23 removably rigid in position on the blocks 20. On each blade 23 there is pivoted at 25 a clamp 24. The strip of metal which forms the clamp is so folded or bent that it resiliently embraces the blade 23 along one side for gripping the carbon-sheets 33, as indicated in Figures 1, 2 and 4. One way of pivoting the clamp 24 on the blade 23 is illustrated in detail in Figure 6, which shows that the pivot-pin 25 is secured in the bar 23. Each pivot 25 may have a knurled head 26 for assisting in the removal of the bar 23 from its pinned position on block 20. When the blades and clamps forming units are being lifted from the blocks 20 the pins 22, provided on the under side of the blades 23, slide out of the holes 21. The clamps 24 may have suitable outwardly-extending arms 27 for swinging the same about the pivots 25.

At the outer side of each of the bearing blocks are mounted upon the truck 18 for limited longitudinal to-and-fro movement upstanding flange-like members or latches 28, the upper edges of which are also stepped correspondingly to the stepped bearing blocks 20. Each step of the flange 28 has an open slot or cutout 29 with which the

outer end 27 of the clamp 24 engages when the carbon-holder is placed upon the corresponding step of the bearing block 20, inserting the pins 22 of the bar 23 into the holes 21 of this step. To provide for the limited longitudinal movement of the flange-like members, which hereafter are called latches 28, there are elongated holes or slots 31 arranged in the base-plates 30 of the latches 28. These slots receive the screws 32, which are fastened on the truck 18; the heads of the screws holding the plates 30 slidably down on the truck. As the cutouts 29 of the latches 28 engage the outer ends 27 of the clamping bars 24, the shifting of the sliding latches 28 will lock or unlock the clamping bars.

To facilitate the shifting of the locking and unlocking latches 28, a finger-piece 34 is provided on one of the ends of each latch. Figure 3 shows the latch 28 and the clamping bar 24 in locking position, while Figure 4 shows the position at which the clamps are open and the carbon-sheets released on the bars 23, permitting a shifting movement of the carbon-sheets relatively to the bar 23.

The improved operation is as follows: The blades 23 are first lifted from their pinned positions. Then the carbon-sheets 33 are each folded over and around a blade 23 and gripped in position by its clamp 24. Preferably, as shown in Figure 2, the upper and lower folded portions of the carbon-sheets 33 have their carbonized surfaces face to face. The lower portion of carbon-sheet 33 is made of proper length to extend around the platen and have the leading edge thereof in position for immediate use in typing. The upper portion of the carbon-sheet 33 is left shorter and serves as a reserve supply. Placing the carbon-sheets 33, as explained, tends to avoid smudging of the adjacent overlying plies when the carbon-sheets 33 are shifted between the plies of the webs 37 during the operation of the carbon-holder truck 18. The webs 37 are then passed between the blocks 20 on the carbon-holder truck 18. The bars 23, with the carbon-sheets attached, are next mounted on the bearing blocks 20 of the truck 18, between the plies of the webs 37, in the usual manner, see Figure 1. The leading edges of the webs 37, with the interleaved carbon-sheets 33, are then threaded under the platen 10 to the front paper-table 13, while the platen 10 is in lifted position. The webs 37, interleaved with carbon-sheets 33, are next positioned for typing by means of a gage, not shown, in the usual manner. The platen 10 is returned to its normal typing position and locked in this position by the latches 15 while the typing operation is proceeded with.

When the leading portions of the transfer surface of the carbon-sheets 33 become worn

and exhausted, a new reserve portion can be placed in position by pushing the finger-piece 34 to slide the latches 28 forward. This swings the clamps 24 away from the bars 23 and releases the grip on the carbon-sheets 33, see Figure 4. And while the platen is in its lowered position, gripping the web and interleaved carbons, the truck 18 is pushed rearwardly by means of the handle 36, thus 10 effecting a relative shift between the fingers and carbon-sheets.

Or else while the platen 10 is in its lifted position, and the leading ends of the carbon-interleaved webs 37 are held between the 15 fingers, the carbon-holder truck, supporting the bars 23, may be slowly pushed rearward an amount equivalent to the exhausted portion to be replaced. These operations and movements cause the portions of the carbon-sheets folded about the blades 23 to slip beyond their former clamped positions. Fresh portions of the carbon-sheets in amount equivalent to the leading worn and exhausted portions are thereby exposed for use. 20 The latches 28 are then restored to the locking position in which the clamps 24 again grip the carbon-sheets 33.

The leading sections of the webs 37, together with the exhausted portions of the 25 carbon-sheets 33, are then gaged and severed by means of the usual knife and gage (not shown). These latter are mounted on the front paper-table 13. The following sections of the webs 37 are now ready for 30 typing, and are interleaved with unused portions of the carbon-sheets.

The above operation is repeated each time when it is necessary to replace the worn portions of the carbon-sheets. It is evident that 35 not only will the disclosed improvement result in a saving of carbon-sheets, but also will greatly aid to simplify the billing operation as a whole. It will further save time, since the carbon-sheets need not be replaced as frequently as when no reserve means is provided. The improved simple clamping feature permits loosening of the carbon-sheets from the outside of the fold of the webs. This allows the reserve portions of the carbon-sheets to be easily and quickly positioned for replacing worn and exhausted portions.

It will be understood that the invention is not restricted to the embodiment shown in 45 the drawings.

While these holding and clamping units are shown in the drawings (two on the right hand and one on the left hand side of the truck) this number and arrangement may 50 vary according to requirements, for instance two holders may be mounted on the left-hand side instead of one.

When single superposed webs instead of fan-folded webs are to be used, it may be 55 more convenient to arrange all of the holders

on one side, particularly if only a small number of carbon or ink sheets is to be used.

Variations may be resorted to within the scope of the invention, and portions of the improvements may be used without others. 70

Having thus described my invention, I claim:

1. In a typewriting machine for writing on superposed webs or longitudinal folds of webs and interleaved carbon or ink sheets, 75 the combination with a roller platen, the grip of which on the combined web and carbon-sheets is releasable, of displaceable means for holding carbon or ink sheets of greater length than required for one form 80 or web section, and clamping means for securing a sheet on the holder and gripping the sheet along a line intermediate both ends of the sheet, said clamping means being operable from the outside while remaining between the webs to allow of releasing the grip for shifting the holder relatively to the sheet and to lock the sheet on the holder in the new working position. 85

2. In a typewriting machine for writing on superposed webs or longitudinal folds of webs and interleaved carbon or ink sheets, 90 the combination with a roller platen, the grip of which on the combined web and carbon-sheet is releasable, of means for holding carbon or ink sheets of multiple-form length, 95 and clamping means for securing a sheet on the holder and gripping the sheet along a line intermediate both ends of the sheet, said clamping means being operable from the outside to release the grip thereby permitting 100 relative shifting between the holder and the interleaved carbon-sheet, and to grip the sheet on the holder in the new working position, said holding and clamping means 105 forming units detachably mounted on the sides of the truck carrying the carbon-holders.

3. In a typewriting machine for writing on continuously-fed webs or longitudinal 110 folds of webs having interleaved carbon or ink sheets, the combination with a displaceable roller platen, of a holder adapted to hold a carbon or ink sheet of a length sufficient for two or more forms in such folded 115 condition that the front end of the sheet is ready for use between the end sections of the web, while the remaining part of the carbon is folded over the holder towards the platen to be kept in reserve, a clamping 120 means on the holder to grip the sheet on the latter, and external releasing means to release the grip of said clamping means on the holder to allow shifting of the holder relatively to the carbon-sheet for placing an unused portion of the carbon-sheet into working position. 125

4. In a typewriting machine for writing on superposed webs or longitudinal folds of webs having interleaved carbon or ink 130

sheets, the combination with a liftable roller platen over which the web with the carbon-sheets is fed, of displaceable carbon-sheet holders, each comprising a bar over which the carbon-sheet is folded, and a clamp pivoted near the outer end of said bar to grip the folded sheet on a line intermediate both ends of the sheet, and means for releasing the clamp and locking it again from the outside, 10 said means comprising an outward extension of the clamp and in engagement with the latter, a to-and-fro movable slide.

5. In a typewriting machine for writing on superposed webs or longitudinal folds of webs having interleaved carbon or ink sheets, the combination with a to-and-fro movable carriage which is slidable on longitudinal rails in the rear of the roller platen, of holder-bars for the carbon-sheets, extending inwardly from lateral bearings on the carriage and comprising means for detachably mounting said holder-bars with one end on said lateral bearings of the carriage, and means for clamping a carbon or ink sheet on each holder-bar along a line intermediate its two ends, and means for releasing the clamping grip from the outside, comprising an outward extension of the clamping member and in engagement therewith a to-and-fro movable slide or latch mounted on the side of the carriage.

6. In a typewriting machine for writing on superposed webs or longitudinal folds of webs having interleaved carbon or ink sheets, the combination with a to-and-fro slidable truck which is mounted in the rear of the roller platen, of inwardly-extending holder-blades for the carbon or ink sheets, said holder-blades being detachably mounted 40 with the outer ends on lateral bearings on the truck, means on the holder-blades for clamping a carbon or ink sheet on each holder-blade along a line intermediate its two ends, and means for releasing the clamping 45 grip from the outside, comprising an outwardly-extending arm of the clamping member and, in engagement therewith a to-and-fro movable slide or latch mounted on the side of the truck, the slide or latch being 50 in engagement with all of the clamping members of all of the holder-blades which are mounted on one side of the truck.

7. In a continuous web typewriting machine for typing on a plurality of superposed plies of fan-fold webs having successive detachable forms thereon, a platen, a carbon-sheet-holding means at the rear of the platen, comprising a plurality of transverse holders reciprocatingly mounted to extend between the plies, 55 carbon-sheets fastened, part way of their lengths, to said holders, one end of each portion of the carbon-sheets being left long enough so that the leading edge thereof may be used in typing said forms until exhausted, 60 the remaining portions providing a reserve 65

within the machine to replace those exhausted, and means operable from the outside of the web to simultaneously release the carbon-sheets from all of the holders so that the replacement of the exhausted portions may be 70 quickly effected from said reserve.

8. A carbon-sheet holding device consisting of a blade about which a carbon-sheet is folded, a clamp for gripping the sheet to the blade pivotally mounted at one end thereof, 75 and an arm forming part of said clamp extending beyond the pivotal mounting to provide means to swing the clamp to grip or release the carbon-sheet.

9. A carbon-sheet holding device consisting of a blade about which a carbon-sheet is folded, a clamp for gripping the sheet to the blade pivotally mounted at one end thereof, 80 an arm forming part of said clamp extending beyond the pivotal mounting to provide 85 means to swing the clamp to grip or release the carbon-sheet, a bearing block to which the blade is detachably mounted adjacent the pivotal connection, and means for engaging the arm to control the movement of the 90 clamp.

10. In a continuous billing typewriting machine for typing a plurality of superposed plies of fan-fold webs having successive detachable forms thereon and interleaved with carbon-sheets, a platen, carbon-sheet-holding means at the rear of the platen, said means consisting of a movable carriage, stepped bearing blocks mounted longitudinally on the carriage near the sides thereof, blades about which the carbon-sheets are folded, detachably mounted to the steps of the bearing blocks and extending between said plies and arranged to reciprocate with the carriage, clamps for gripping the carbon-sheets to the blades, pivoted at one end thereof and adjacent the mounting of the blades to the steps of the bearing blocks, and an arm forming part of each clamp extending beyond the pivoting point and outside the folds of the webs by means of which the clamp is swung to grip or release the carbon-sheets.

11. In a continuous web typewriting machine for typing a plurality of superposed plies of webs having successive detachable forms thereon and interleaved with carbon-sheets, a platen, carbon-sheet-holding means at the rear of the platen, said means consisting of a movable carriage, stepped bearing blocks mounted longitudinally on the carriage near the sides thereof, blades about which the carbon-sheets are folded, detachably mounted to the steps of the bearing blocks and extending between said plies and arranged to reciprocate with the carriage, clamps for gripping the carbon-sheets to the blades pivoted at one end thereof and adjacent the mounting of the blades to the steps of the bearing blocks, an arm forming part 115 120 125 130

- of each clamp extending beyond the pivoting point outside the folds of the web by means of which the clamp is swung to grip or release the carbon-sheets, and a single means 5 on the carriage engaging all of said arms to control the movement of the clamps.
12. In a continuous web typewriting machine for typing on a plurality of superposed plies of web having successive detachable forms thereon, a platen, carbon-sheet-holding blades at the rear of the platen reciprocatingly carried mounted upon a stepped series of mounts so as to extend between the plies, carbon-sheet-clamping means 10 associated with each blade, each blade having a carbon-sheet folded part way of its length around the blade and gripped thereto by said clamping means, one portion of each sheet being in use and the remaining portion providing a reserve within the machine, means for simultaneously releasing a plurality of said clamping means to free the carbon-sheets from the blades, said blades being interchangeable upon any of 15 the mounts, said releasing means being brought into operative relation with said blades upon the act of attaching them to their mounts, and manually-operable means for effecting a relative shift between each 20 blade and associated carbon-sheet to substitute a reserve portion for the used portion without removal of the carbon-holding blades from between the plies of the web.
13. A carbon-sheet holder for use in typewriting machines, including a clamp for securing a carbon-sheet between two plies of material, and means at the exterior of said plies operatively connected to said clamp for releasing the carbon-sheet.
14. In a typewriting machine for writing on successive detachable forms of a web, a blade for engaging the intermediate portion of a carbon-sheet interleaved between adjacent plies of the web, a clamp for securely 25 holding the carbon-sheet to the blade, means at the exterior of the web operatively connected to said clamp for releasing the carbon-sheet from said blade after the leading form has been typed, and means for slipping the blade beyond said first-mentioned carbon-holding position to make available an unused carbon portion, the leading used portion being removed together with the detachable typed form.
15. A carbon-retracting device for use in 55 a typewriting machine for writing on successive detachable forms of a fan-fold web with a carbon-sheet, partially folded upon itself and providing a leading exposed portion, interleaved between adjacent plies of the web, including removable carbon-holding blades, each engaging the bight of a carbon-sheet, said blades being supported upon a stepped series of mounts on said carbon-retracting device and carrying clamps for holding the sheets onto the blades, means for simultaneously releasing the clamps, said clamps each including an arm extending to the outside of the web-plies, the blades and their clamps being interchangeable to 60 any of the mounts, said releasing means being brought into operative relation with the clamp-arms upon the act of attaching the blades to any of said mounts, and manually-controlled means for operating the carbon-retracting device to effect a relative shift between the blades and the released carbon-sheets.
16. A carbon-retracting device for use in 65 a typewriting machine for writing on successive detachable forms of a fan-fold web with a carbon-sheet, partially folded upon itself and providing a leading exposed portion, interleaved between adjacent plies of the web, including removable carbon-holding blades, each engaging the bight of a carbon-sheet, said blades being supported upon a stepped series of mounts on said 70 carbon-retracting device and carrying clamps for holding the sheets onto the blades, means for simultaneously releasing the clamps, said clamps each including an arm extending to the outside of the web-plies, the blades and their clamps being interchangeable to 75 any of the mounts, said releasing means being brought into operative relation with the clamp-arms upon the act of attaching the blades to any of said mounts, and manually-controlled means for operating the carbon-retracting device to effect a relative shift between the blades and the released carbon-sheets.
17. A carbon-retracting device for use in 80 a typewriting machine for writing on successive detachable forms of a fan-fold web with a carbon-sheet, partially folded upon itself and providing a leading exposed portion, interleaved between adjacent plies of the web, including removable carbon-holding blades, each engaging the bight of a carbon-sheet, said blades being supported upon a stepped series of mounts on said 85 carbon-retracting device and carrying clamps for holding the sheets onto the blades, means for simultaneously releasing the clamps, said clamps each including an arm extending to the outside of the web-plies, the blades and their clamps being interchangeable to 90 any of the mounts, said releasing means being brought into operative relation with the clamp-arms upon the act of attaching the blades to any of said mounts, and manually-controlled means for operating the carbon-retracting device to effect a relative shift between the blades and the released carbon-sheets.
18. A carbon-retracting device for use in 95 a typewriting machine for writing on successive detachable forms of a fan-fold web with a carbon-sheet, partially folded upon itself and providing a leading exposed portion, interleaved between adjacent plies of the web, including removable carbon-holding blades, each engaging the bight of a carbon-sheet, said blades being supported upon a stepped series of mounts on said 100 carbon-retracting device and carrying clamps for holding the sheets onto the blades, means for simultaneously releasing the clamps, said clamps each including an arm extending to the outside of the web-plies, the blades and their clamps being interchangeable to 105 any of the mounts, said releasing means being brought into operative relation with the clamp-arms upon the act of attaching the blades to any of said mounts, and manually-controlled means for operating the carbon-retracting device to effect a relative shift between the blades and the released carbon-sheets.

JESSE A. B. SMITH.
